GLIDER FOR HAND VACUUM CLEANERS

Edgar P. Turner, Fanwood, N. J., assignor to The
Singer Manufacturing Company, Elizabeth,
N. J., a corporation of New Jersey

Application May 14, 1949, Serial No. 93,382

3 Claims. (Cl. 280—12)

1

This invention relates to vacuum cleaners and more particularly to a means whereby a vacuum cleaner of the type that is ordinarily held in one hand, and commonly known as a hand vacuum cleaner, may be provided with an extension hose and supporting runners so that the hand vacuum cleaner can be placed on the floor and pulled around by the hose.

The principal object of the present invention is to provide a glider that can easily be attached to or removed from a hand vacuum cleaner.

Another object of the invention is to provide an improved means that will render a hand vacuum cleaner usable selectively as a hand vacuum cleaner or in the same manner in which a tank type cleaner is usable.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings—

Fig. 1 is a side elevational view of a hand vacuum cleaner equipped with a glider embodying the present invention, and Fig. 2 is a perspective view of the glider.

The single sheet of drawings, forming a part of this specification, illustrates a hand vacuum cleaner 10 supported by a wire frame or glider 11. The vacuum cleaner includes, among other items, a fan casing 12 and a motor housing 13, the two being held together by screws 14. The fan casing 12 has an intake 16, and an exhaust (not shown) to which a dust bag 17 is attached. A carrying handle 18 has its front terminal 19 secured to the fan casing 12 and its rear terminal 21 secured to the motor housing 13. The rear terminal 21 of the handle 18 is bent and thereby protrudes rearwardly beyond the end of the motor housing 13. The intake 16 of the fan casing 12 has, protruding from its forward end, a reduced neck which may be formed integral therewith or as indicated in Fig. 1 may be in the form of a separate pipe 22 entering a recess 23 provided in the intake 16. While the drawing shows the pipe 22 as having a tapered inner end that fits into the tapered recess 23 formed in the intake 16, it will be understood that any other suitable type of connection may be employed.

The end of the tube 22 remote from the fan casing 12 is attached to a flexible hose 26 by a

conventional connector means not shown. The free end of the hose 26 is adapted to receive a variety of attachments of which only one, a nozzle 27, is shown.

5 The glider 11 is formed from a single piece of wire that is preferably circular in cross section and bent to provide a pair of slightly divergent-convergent runner portions 31—31'. The diverging ends of the runners 31 and 31' are bent upwardly and backwardly, as at 32 and 32', and thereby form a pair of upstanding convergent wire portions 30—30'. The upper ends of these upstanding portions are bent downwardly as at 33—33' and thereby merge into a centrally located U-shaped loop 34 fashioned to receive the intake pipe 22 of the hand vacuum cleaner 10.

The longitudinal axes of the upstanding wire portions 30 and 30' preferably define a plane that intersects, at an angle of approximately seventy-five degrees (75°), a plane defined by the longitudinal axes of the runners 31 and 31'. The portion of the wire which forms the loop 34 lies in a vertical plane that is substantially normal to the plane defined by the axis of the runners 31—31'. 15 The dimensions of the loop 34 are such that the wire frame has to be sprung slightly when the pipe 22 enters the loop 34, thus insuring proper holding of the pipe by the loop.

At the other end of the glider, where the runners converge toward one another, wire portions 35—35', extending from the runners 31—31', are bent, as at 36—36', so as to be upstanding and convergent. The upper ends of these upstanding portions are bent, as at 37—37', to form horizontally and coaxially positioned portions 40—40'. The proximate ends of these horizontal portions are bent as at 38—38' to form centrally located portions of the wire that are adjacent and parallel. These adjacent portions are joined by welding 39. Above the welded joint 39, the wire portions are bent outwardly at 41—41' and upwardly at 42—42' thereby providing upstanding resilient ends 43—43' that are each covered with rubber tubes 44—44' and comprise the tines of a fork. The rubber covered portions of the glider form a substantially U-shaped member designed to receive the bent portion 21 of the vacuum cleaner handle 18. Reference to Fig. 1 shows that the axes of all of the portions of the wire above bends 36—36' lie substantially in a plane that is transverse to the plane defined by the axis of the runners 31—31' and at the same time makes an angle of approximately fifty degrees (50°) therewith.

When it becomes desirable to use the hand

vacuum cleaner in the manner in which a tank type cleaner is normally used, the hand cleaner 10 is attached to the glider 11 by snapping the pipe 22 into the loop 34 and by forcing the rear terminal 21 of the handle 18 between the rubber covered resilient ends 43-43'. After the hose 26 has been attached to the pipe 22, the cleaner 10 and the glider 11 are placed on the floor with the runners 31-31' resting thereon. The cleaner 10 and glider 11 are then pulled around the room by means of the hose 26 and any desired cleaning tool, as for example the nozzle 27.

Having thus set forth the nature of the invention, what I claim herein is:

1. A glider for use with hand type vacuum cleaners, comprising, a wire frame bent from a single piece of wire, said frame having a pair of wire runners, a pair of wire portions upstanding at one end of said glider and converging toward one another, a U-shaped bend joining the upper ends of said upstanding portions, a second pair of wire portions upstanding at the other end of said glider and converging toward one another, a pair of horizontal coaxial wire portions extending toward one another from the upper ends of said second upstanding portions and, a pair of parallel adjacent portions extending upwardly from ends of said horizontal portions, and a pair of outwardly and upwardly bent portions extending from said parallel portions, said parallel portions being welded together and said outwardly and upwardly bent portions being covered by rubber tubes.

2. A glider for use with hand type vacuum cleaners, comprising, a wire frame bent from a single piece of wire, said frame having a pair of convergent wire runners, a pair of upwardly convergent wire portions rising from one end of said glider and defining a plane vertically inclined at an angle of approximately seventy-five degrees to a horizontal plane containing said runners, a U-shaped bend joining the upper ends of said up-

wardly convergent wire portions, a second pair of upwardly convergent wire portions rising from the other end of said glider, said second pair of wire portions defining a plane vertically inclined at an angle of approximately fifty-degrees to the plane of said runners, a pair of horizontally disposed coaxial wire portions extending toward one another from the upper ends of said second upwardly convergent wire portions and terminating in a pair of parallel upwardly-inclined adjacent portions, and a pair of outwardly and upwardly bent portions extending from said parallel portions, said parallel portions being welded together and said outwardly and upwardly bent portions being covered by rubber tubes.

3. A glider for use with hand type vacuum cleaners, comprising, a wire frame, said frame having a pair of wire runners, a pair of upwardly convergent wire portions rising from one end of said glider, a U-shaped bend joining the upper ends of said upwardly convergent wire portions, a second pair of upwardly convergent wire portions rising from the other end of said glider, a pair of horizontally disposed wire portions extending toward one another from the upper ends of said second upwardly convergent wire portions and terminating in a pair of parallel upwardly inclined adjacent portions, and a pair of outwardly and upwardly bent portions extending from said parallel portions, said parallel portions being secured to one another.
